ABSTRACT: A business machine such as an adding machine, cash register, or the like is provided with two accumulators which have respective sets of registers which are interleaved with one another and which are mounted on the same shaft. U-shaped bails interconnect lower order registers with associated registers representing higher digital orders. Camming surfaces and additional mechanisms operating on each transfer bail condition the bails to provide carries under appropriate conditions as the entire accumulator assembly is moved from its operating position to its rest position. By these arrangements, positive, simultaneous transfers are accomplished subsequent to the entry of digital information, in both of the two interleaved accumulators.

TRANSFER MECHANISM

This invention relates to business machines, and more particularly to transfer mechanisms for effecting carries in adding machines, cash registers, or the like.

CROSS-REFERENCES TO RELATED APPLICATIONS

This invention is closely related to two prior patent applications which disclose the structure of a cash register. These cases are Kenneth F. Oldenburg, U.S. Pat. application, Ser. No. 50,064, filed June 26, 1970, entitled BUSINESS MACHINE; and Paul Greskovics, U.S. Pat. application, Ser. No. 50,063, filed June 26, 1970, entitled MECHANICAL MECHANISM.

BACKGROUND AND SUMMARY OF THE INVENTION

Many different mechanical mechanisms have been proposed heretofore for implementing the transfers required in adding machines. Thus, when the five lowest order registers of an adding machine accumulator stand at "09,999," and a "1" is added to the units order, the units order register is shifted to the "0" state, the next three registers must also be shifted to "0," and a final "1" is inserted at the highest order, so that the output from the accumulator will read "10,000."

A number of classic types of transfer mechanisms for implementing such functions are well known in the art. Some of these involve what is known as a sequential carry where the carries successively trip over from the least significant order to the most significant order. Other mechanisms require cumulative action from one order to the other with springs often providing the driving force. In this regard, it is most desirable that the mechanical forces act positively to give the correct carry, rather than through spring actuation or through tolerances which may build up over several orders and thus produce errors.

In addition, the mode of application of power is important and more specifically, mechanical power should not be transmitted through a long chain of mechanical elements. Instead, sufficient local power should be applied at each order to positively actuate each of a full sequence of transfers, even though many orders are involved. Overly complex mechanisms including large numbers of parts can also present problems. It is important to have as few parts as possible involved in the transfer mechanisms, both to cut down possibilities for malfunctions and to simplify assembly of the business machine.

The transfer mechanism of the present invention includes a number of novel aspects. In accordance with one of these aspects, a single transfer bail interconnecting adjacent registers of different digital order is designed to perform a large number of functions. Specifically, each transfer bail may include structural features selected from the following: (1) a cam follower to sense the state of the lower order register, (2) a lower order actuating surface to receive bail position information from the next lower order transfer bail, (3) a higher order actuating surface to transmit bail position information and cooperate in shifting the position of the adjacent higher order transfer bail, (4) a latching portion, and (5) a transfer hook or extension to implement a transfer or carry once the transfer bail is shifted to the actuated state. The wedges which act on each pair of adjacent bails to establish transfers represent another feature of the invention.

In accordance with another aspect of the invention, the accumulator assembly includes two accumulators having two sets of registers interleaved with one another and mounted on a single shaft. Two corresponding sets of U-shaped transfer bails are provided for interconnecting alternate registers forming a single accumulator to provide a positive, simultaneous transfer which occurs subsequent to the entry of digital information.

In accordance with another feature of the invention, a positive, simultaneous transfer is accomplished subsequent to the entry of digital information as the accumulator is being restored from its operating position to its rest position.

Other aspects and features of the invention will become apparent from a consideration of the following description and the drawings in which:

5 FIG. 1 is an assembly view of a business machine or cash register embodying the principles of the invention;

FIG. 1A is a fragmentary top view of the machine of FIG. 1;

FIG. 2 is a partially exploded view of the cash register of FIG. 1;

10 FIG. 3 is a perspective view of certain key elements of the accumulator assembly;

FIGS. 4(a) through 4(i) are a series of diagrammatic representations of the possible conditions of the transfer mechanism of FIG. 3;

15 FIG. 5 shows a single transfer bail;

FIG. 6 is a rear view of the accumulator assembly of the business machine;

FIG. 7 is a schematic cross-sectional view of the cash register of FIG. 1;

20 FIG. 8 is a side view of the certain critical operating parts of the accumulator and the transfer mechanism;

FIG. 9 is a top view of the accumulator assembly showing the two interleaved sets of registers and all of the transfer bails;

25 FIGS. 10 and 11 are side views and cross-sectional views, respectively, of one of the cams which actuate the bails which figure in the accumulator transfer operation; and

FIG. 12 is a timing chart for the business machine.

Referring more particularly to the drawings, FIG. 1 shows a 30 cash register in accordance with the invention in which the cash drawer 22 forms a base for the mechanical and calculating portion of the cash register 22. FIG. 1A is a view from above showing the display windows 24 and 26 which are visible to the cash register operator and display window 28 which

35 may be observed by the customer. The display window 24 shows the subtotal, while the display windows 26 and 28 show identical item amounts.

FIG. 2 is an exploded view of the cash register, showing the principal assemblies of the upper portion 22 of the cash register of FIG. 1. In FIG. 2, the principal components are the accumulator 100 to which the present specification is primarily directed, the keyboard 200, the indicator 300, and the base and power unit 400. Also visible in FIG. 2 are the transfer hooks forming part of the bails 102 which constitute an important part of the accumulator operating mechanism.

The overall mode of operation of the cash register is described in detail in the above-referenced patent applications of Messrs. Oldenburg and Greskovics. However, referring to FIG. 2, it may be noted that the accumulator moves down from a rest position into engagement with perforated digit tapes or racks, and then, following digitation by the operation of the perforated digit tapes, the accumulator is raised to its rest position. The movement of the accumulator up and down is accomplished by the sets of eccentrics 104. For clarity, these eccentrics 104 and the plate in which they operate are shown twice in FIG. 2, both with the accumulator assembly, and with the base. The stops on the digit tapes are shown in FIG. 2 at 105. These stops move from left front to right rear in the showing of FIG. 2, until they engage a depressed key which stops their motion. The gears 106 of the accumulator assembly 100 are meshed with the perforated digit tapes during this movement of the tapes, and the gears are therefore rotated by an amount corresponding to the digits recorded in the keyboard.

The transfer mechanism which forms the central subject of this specification will be described in connection with FIG. 3 of the drawings. For purposes of clarity of description, only the essential elements of the mechanism are included. To relate FIG. 3 with FIG. 2, the accumulator gears 106 shown in FIG. 2 are designated by the reference numerals 106, 106' and 106'' in FIG. 3. As disclosed in more detail elsewhere, the accumulator assembly actually includes two sets of interleaved registers each forming an accumulator. However, only one set of registers forming a single accumulator is shown in FIG. 3.

The central elements in the transfer mechanism are the transfer bails 102, 102' and 102''. The transfer hooks 108, 108' and 108'' of the transfer bails 102 are selectively coupled with the dowels or pins 110' which protrude from the register wheels 106. The register wheels or discs 106 include peripheral gear teeth 112, a cylindrical numbered area 114 and a camming surface 116, having three cam levels 120, 122 and 124.

As discussed above, the accumulator wheels 106 are mounted on a single shaft and, during an add operation, move down from the rest position into the operating position and then back to the rest position in the direction indicated by the arrows 118 in the center of each of the register wheels 106. The purpose of the transfer mechanism which is being described is to move the transfer hook 108 into coupling engagement position with a pin 110 of one of the transfer wheels when a carry should properly be included in the next higher order. With reference to the right-hand bail 102, it may be seen that the transfer hook 108 is in appropriate overlying relationship with one of the dowels 110' associated with register wheel 106'. In passing, it may be noted that even with the hook 108 in the latched actuating position, the pins 110' still clear the hook to permit further rotation of gear 106'. The transfer hook 108', however, has not been rotated into its actuated position overlying any of the dowels 110'' of register wheel 106''.

Incidentally, the register wheel 106 represents the least significant or units order, while register wheel 106' represents the tens order and register wheel 106'' represents the hundreds order.

Each of the register wheels is provided with a camming surface 116. The camming surface has three elevations. One elevation corresponds to the register digit positions "0" through "8." A second elevation 122 represents the digit "9," and a third elevation 124 is effective as a gear moves from "9" to "0." A cam follower portion 126 on one arm of the transfer bail 102 rides on the cam surface 120. Once a lower order register wheel has passed through "0," its associated transfer bail locks into the most advanced clockwise position, as shown in FIG. 3, and a transfer in the next higher order occurs as the accumulator register is restored from its operating to its rest position. Thus, by way of example, in FIG. 3, it may be seen that the cam follower surface 126 of transfer bail 102 is resting on the surface 124 of the cam 120, thus rotating transfer bail 102 to its extreme clockwise position so that the transfer hook 108 overlies a pin 110' on the next higher order register wheel 106'. Note further that the latch 128 associated with a corner 130 of transfer bail 102 latches the transfer bail 102 into its operated position so that as the units order register wheel 106 is rotated past the "0" state, the transfer bail 102 remains in its fully operated counterclockwise position.

Similarly, of course, the tens and hundreds order registers are identically interrelated. Thus, when the tens order register wheel 106' passes through the "0" state, the transfer bail 102' is latched into its extreme counterclockwise position and transfer hook 108' is moved forward from the position shown in FIG. 3 so it overlies one of the pins 110' and rotates register 106' when the accumulator assembly is moved upward. It may also be noted in FIG. 3, that the latch 128' is not latched into position on the corner 130' of transfer bail 102', but is merely biased into engagement with its outer surface.

In the foregoing description, we have discussed a simple, one-stage transfer from one order to the next higher order. The more difficult case is where a series of registers are set in the "9" state and an additional unit is added to the lowest order register. In this case, a more complex sequence is required for implementing the transfer.

In the arrangement shown in FIG. 3, the tens and the hundreds order wheels are in the "9" position and the units order has just been actuated through "0." Under these conditions, both the tens order register wheel 106' and the hundreds order register wheel 106'' must be advanced by one unit as the accumulator register is shifted back in the vertical direction to

its rest position. There is no problem with the primary transfer for the tens order resulting from the unit order having reached "0" or passed through "0." This causes the rotation of transfer bail 102 as described above so that the latch 128 engages corner 130 of the bail 102 and the transfer hook 108 is latched into the transfer condition.

However, the situation with the hundreds order is slightly more complex. Thus, the transfer bail 102' has not been rotated into the latched position. Instead, the cam follower surface 126 is resting on the surface 122' representing the "9" condition of register wheel 106' of the tens order. The additional transfer is accomplished by the action of the wedge 132 and its interaction with the actuation surfaces 134 on bail 102 and 136' on bail 102'. The wedge 132 is moved forward, to the right and upward in the showing of FIG. 3 and is initially controlled in its angle of engagement with surfaces 136' and 134. If cam follower surface 126' is in any of the "1" through "8" states, the wedge 132 will ride over the top of the tail associated with surface 136' on transfer bail 102'. Then, of course, no rotation of transfer bail 102' will occur. However, if cam follower surface 126' is in engagement with the "9" surface 122' of the cam, and if transfer bail 102 is latched up in a counterclockwise direction so that surface 134 is located in a relatively high position, then wedge 132 will push on surface 136' and rotate transfer bail 102' in the clockwise direction so that it will be latched up into the transfer position. This will, of course, be accomplished by latch 128' engaging corner 130' of transfer bail 102'.

Similarly, wedge 132' will rotate bail 102'' to the actuating position by its wedging action between surface 134' and 136''. Thus, as bail 102' is being rotated into its latched position, wedge 132' will operate on surface 136'' of bail 102'' so that, while the latching of bail 102' is taking place, full rotation of bail 102'' to its operated position will also take place. In connection with the foregoing description, attention is particularly directed to the application of actuating forces at each order where transfers are taking place through the use of the wedges 132, 132', etc.

Now that the principles underlying the mode of operation of the transfer arrangements have been described, the mechanical implementation of the operations described above will be further described, and details of various mechanisms which are employed and the various possible conditions of operation will be discussed.

In FIG. 3, the transfer bails 102 rotate about a shaft (not shown) located on a fixed axis 138. The lifting bail 140 also rotates about axis 138. The bail 140 carries the shaft 142 which serves to position the transfer bails 102 during digitation, or rotation of the registers 106 by the digit tapes. Specifically, the lifting bail 140 rotates to engage the lower surface of each transfer bail near the corner 130 and rotate the bail to the "9" level. Were this not done, the sudden actuation of the cam follower surface 126 on the transfer bails might throw the transfer bails beyond the "9" level, so that they would be improperly latched into the transfer state. The timing of this operation of the transfer bails is shown in the chart of FIG. 12 of the drawings. The cam operation of the lifting bail 140 will also be set forth in greater detail below.

Incidentally, the recesses 144, in the lifting bail 140 and the hole 146 in one end of the transfer bail 102, provide the securing points for a coil spring which bears against the latch 128 between the spring retaining elements 148 to bias the latches 128 in the clockwise direction and to exert a counterclockwise torque on the transfer bails 102.

The wedge bail 150 pivots about the fixed axis 152 and carries the wedges 132 on shaft 154. The wedges each have a recess 156 which slide onto a fixed shaft when they are in the counterclockwise or retracted position. As the wedges are cammed forward in the clockwise direction, they are initially guided by the fixed shaft (not shown) so that their forward surfaces will properly engage surfaces 136 and 134; thereafter, as the slots 156 leave the fixed shaft, the wedges are free to tilt upward or downward about the shaft 154 as

required by the positions of the surfaces of the transfer bails. The timing of the actuation of the transfer wedge is also shown in FIG. 12.

FIGS. 4(a) through 4(i) are a series of diagrams showing the operation of the wedges 132 for various possible sets of conditions of the units register and the tens register.

Thus, in FIG. 4(a) the units cam is in the "0-to-8" position and the tens cam is also in the "0-to-8" position. Under these circumstances, the wedge 132 rides over the top of the control tails carrying actuation surfaces 134 and 136, and no actuation of the transfer bails occurs.

Similar action occurs in the situations depicted in FIGS. 4(b) and 4(c). The transfer bail 102 is already latched up into the transfer condition, and no transfer is appropriate for the hundreds order; accordingly, the transfer wedge rides over the top of both control tails.

In FIG. 4(d), the control surface 136' is positioned for actuation if the units control surface 134 were in the raised position; however, with the units transfer bail being in the "0 through "8" state, the wedge passes into the space between the two control tails and no transfer action takes place.

The same situation exists in FIG. 4(e), with the wedge fitting between the two control surfaces, but not actuating the higher order transfer bail.

In FIG. 4(f), step No. 1, the wedge 132 is entering between the closely spaced surfaces 134 and 136'. In FIG. 4(f), step No. 2, the wedge 132 has actually forced surface 136 upward to rotate transfer bail 102' in the clockwise direction and introduce a carry in the hundreds order. FIGS. 4(g), 4(h) and 4(i), show various arrangements where the wedge performs no positive function but merely fits between the units and tens control surfaces.

FIG. 5 is a perspective view of the transfer bail 102 of FIG. 3. It has been shown alone to emphasize the many functions performed by its various components. Thus, as mentioned above, the surface 126 serves as a cam follower. The transfer hook 108 provides carry action as the accumulator is restored from its operating to its rest positions. The surface 136 is a higher order actuating surface which, in combination with the wedge, produces carries in the next higher order under appropriate circumstances. The lower corner 130 of one arm of the transfer bail 102 serves to engage the latch 128. In addition, the lower surface 158 of the one control tail of the transfer bail 102 serves as a stop to engage the lifting bail so that the angular position of the transfer bail may be accurately determined. The transfer bail 102 also includes the hole 146 to which a biasing spring is secured to normally rotate the bail in the counterclockwise direction.

As noted above, the transfer bail provides many closely interrelated functions. Despite the many functions which it provides, it essentially is a simple sheet metal stamping with two bends. Because of the many functions provided by this simple sheet metal stamping, simplicity in the mechanical mechanism and ease of assembly are achieved.

In the balance of the detail description, many of the other mechanical components of the cash register will be described for purposes of completeness.

In FIG. 6, the accumulator assembly 100 is shown from the rear. Above the accumulator assembly, slideable viewing arrangements 160 are provided to permit viewing one set of register wheels or the alternate set of wheels which are interleaved with them. In this connection, it may be noted that in the particular business machine which is described, one set of registers may provide the subtotal while the other set of interleaved register wheels provide the grand total for the day.

In FIG. 6, the digit tapes 162 actuate the register wheels 106 and 107 by engagement with the respective sets of gear teeth on the registers 106 and 107 in the two sets of perforations in the digit tapes 162. Incidentally, the stops 105 shown in FIG. 2 are secured to the digit tapes 162 of FIG. 6.

In the diagrammatic showing of FIG. 7, the accumulator 100 is shown immediately below the viewing windows 160. Other relevant major mechanical portions of the cash register

assembly are labeled in FIG. 7, and are described in detail in the above-referenced cases of Messrs. Oldenburg and Greskovics. The cam line 166 and the center portion 168 of the accumulator assembly in the rest position are of particular interest in connection with FIG. 8 which will now be described.

With reference to FIG. 8, it is useful initially to note the relationship to FIG. 7 of the drawings. In this connection, note point 166 which is the center of the cam line, and point 168 which is the rest position for the center of the accumulator. In FIG. 8, however, the accumulator is actually shown in its shifted or operating position, with the center of the accumulator at point 170. Other components which were shown in FIG. 3 include the transfer bail 102, the lifting bail 140, the wedge 132 and the wedge bail 150.

Concerning the transfer bail 102, it is in the unactuated or "0-to-8" position in which the transfer hook 108 is spaced back from the pins or dowels 110. When the transfer bail is rotated counterclockwise to its operated position just above one of the pins 110, and the accumulator register is moved upward from position 170 to the rest position 168, the accumulator register 106 is advanced by one digit to complete a carry operation. Overthrow protection is provided by having the hooks 108 interact with two of the pins 110, and by delaying the release or "knocking out" of the bail latches for a short period of time after the accumulator moves back to its rest position. The cam follower surface 126 may also be noted, and it may be observed that the cam surfaces 122 corresponding to 30 the "9" position, and the cam surface 124 which would engage cam follower surface 126 when the register goes through "0," are not operative in the showing of FIG. 8.

As noted previously, the transfer bails 102 have two tails which extend to the left in the showing of FIG. 8. In the foreground in FIG. 8, the surface 136 is shown at an elevation slightly above the higher order actuating surface 134. Other portions of the transfer bail 102 visible in FIG. 8 include the latching corner 130 and the hole 146 to which one end of biasing spring 172 is secured.

40 The biasing action of tension spring 172 may be clearly seen in FIG. 8 in which the lower end of spring 172 is secured to the recesses 144 in the lifting bail 140. The spring 172 both biases the transfer bail 102 in the counterclockwise direction and biases the latch 132 in the clockwise sense.

45 It is noted in passing that transfer bails 102 and the lifting bail 140 are mounted on the fixed axis 138. The latch 132 is mounted on the fixed shaft 174. The latch knockout bail 176 is also pivoted about shaft 174 and is actuated at the end of each cycle as shown on timing chart FIG. 12 to permit restoration of transfer bails 102 to their counterclockwise or unoperated conditions. The fixed shaft 178 gives direction to the initial movement of the wedges 132 as they are moved forward by the action of the wedge bail 150 to which they are pivoted secured by shaft 180. The wedge bail 150 is pivotally mounted for rotation about fixed axis 152.

50 The three bails 140, 150 and 176 are operated by dual cams which are mounted near the opposite ends of the cam line centered at point 166. The bails are provided with two cam pins, one on each side of the machine, which interfit with the recesses in the cam which is shown in FIGS. 9 and 10. Lifter bail 140 is provided with a cam pin 182; the wedge bail is provided with cam pin 184, and the latch knockout bail is provided with cam pin 186. These cam pins fit into channels in the transfer cam as shown and described below.

55 FIG. 9 is a top view of the accumulator assembly. Visible in FIG. 9 are the registers 106 and the bails 102 which were shown broken out from the remaining structure in the isometric view of FIG. 3.

60 With regard to showings of FIG. 3 and FIG. 9, it should particularly be noted that the portions of the U-shaped bail forming the base of the "U" may be located at different points to provide suitable clearance between parts. In the showing of FIG. 9, for example, the numbers 102 are applied to the interconnecting portion which is located along the tail structures

rather than close to the pivot point, to provide clearance for the transfer bails 103 which are associated with the interleaved register.

To distinguish between the two registers, the subtotal accumulator register wheels are designated by the reference numeral 106 and the associated transfer bails are designated by reference numeral 102. The grand total accumulator, however, includes registers designated by reference numerals 107 and 107', and the transfer bails designated 103 and 103'. In connection with the interpretation of FIG. 9, it may also be noted that the reference numerals 102 and 103 in each case are associated with the base or interconnecting portion of the transfer bails 102, 103, or 103'. Particularly in connection with the transfer bails 103 and 103' employed with the grand total register wheels 107 and 107' the position of the base portion is shifted from one transfer bail to the next to provide adequate clearance. It may also be noted that the grand total accumulator has two more orders or registers than the subtotal accumulator. This is obviously desirable to accommodate the larger numbers which will be included on a full day's transactions. The registers 107' do not have gear teeth which engage digit tapes but merely accommodate overflow from the other registers which do receive information directly from the digit tapes. The transfer bails 103 and 103' supply transfer information to the higher order grand total accumulator registers 107. The pins 110 for both the grand total registers and the subtotal are visible in FIG. 9. It is also noted that the lifting bail, the latch knockout bail, and the wedge bail all serve both of the two accumulators in each machine cycle.

FIGS. 10 and 11 show side and cross-sectional views of the bail actuating cam 188 which is mounted on cam line 166. In FIG. 10, the opening 190 in the center of the cam line conforms to the grooved shape of the cam line shaft to which it is rigidly secured. Two cams which are mirror images of each other, are employed at opposite sides of the business machine to actuate the various accumulator bails in a positive manner. As shown in FIG. 11, the cam 188 is two-sided, and is provided with cam pin receiving recesses on both of its surfaces. In FIG. 10, the two recesses which are shown are the latch knockout cam track 192 and the wedge bail cam track 194. Two other tracks 196 and 198 are located on the other side of cam 188.

FIG. 12 shows a timing chart of certain critical operations of the cash register under consideration. The chart plots the 360° rotation of the cam shaft which is mounted on axis 166 as shown in FIGS. 7 and 8, for example. In the chart of FIG. 12 the action of the tapes in their initial restoring action and subsequent selection function is shown as extending from 0° to 100° for restoration and from 140° to 280° for selection. The chart also shows the accumulator shifting from its rest position to the operating position between 100° and 140° and restoring to the rest position between 310° and 340°. Concerning the transfer bails 102, the chart shows that the lifting bail 140 has rotated the transfer bails to the "9" position during the interval from 0° to about 100° prior to the start of the selection portion of the cycle. As previously mentioned, this avoids imparting undesired momentum to the transfer bails and throwing them into the latched position when the registers reach the "9" position. At the end of the selection cycle at 280°, the transfer bails are allowed to return to their extreme counterclockwise position, if they have not been previously latched into their operating position by the digit selection action, or if the controlling register is not at its "9" position.

The wedge bail action starts at 290° and continues in the forward direction to 310° and is then fully retracted by the 340° point in the cycle. Any transfer bails which are to be latched up will therefore be latched by the 310° point in the cycle. As mentioned above, the accumulator restoration occurs from 310° to 340°. During this interval, the transfer hooks 108 of the transfer bails 102 will have provided all appropriate carries, as the vertical movement of the accumulator assembly causes engagement of the transfer hook with transfer pins 110. The latch knockout bail 176 operates at the 350° point in the

cycle and permits full restoration of all of the transfer bails 102 to their counterclockwise (unlatched) positions at the end of the cycle.

As mentioned in the introduction of this specification, important features of the present invention include the many functions performed by the single transfer element inter-coupling successive registers of each of the interleaved accumulators, and the implementation of the carry function as the register is being transferred from its operating portion to the rest position. The positive, simultaneous transfer, subsequent to the entry of the digital information was also considered to be important in the context of the other features.

In the introduction of this specification, mention was made of the existence of other prior art mechanisms for performing the transfer function. Some of these prior references include two patents of Herman Gang, U.S. Pat. Nos. 3,102,688 and 3,472,450, granted on Sept. 3, 1963 and Oct. 14, 1969, respectively; O. M. Phillip, U.S. Pat. No. 2,701,100, granted Feb. 1, 1955; and W. H. Brown, U.S. Pat. No. 1,214,886, granted Feb. 6, 1917. The two Gang patents disclose related types of transfer mechanisms; however, interleaved registers are not employed. In addition, the mechanisms are somewhat more complex than those of the present invention, in view of constraints imposed by the design criteria of the machine. The Phillip patent has one similarity, that of using interleaved registers; however, a sequential type carry rather than the simultaneous carry included in applicant's apparatus, is employed and many other differences are present. The Brown patent is pertinent in the use of a transfer mechanism which operates as the position of the accumulator is shifted. However, the Brown patent is not concerned with interleaved accumulators and is quite different in its mode of operation in many other respects.

In closing, it is to be emphasized that the present invention is not limited to the exact form shown in the drawings. Instead, for example, the principles of the invention are applicable to three accumulators with registers alternated on a single shaft; in addition, certain principles of the invention are applicable to a single accumulator, and to accumulators in which both addition and subtraction occurs. Also, the transfer bail could be implemented in a mechanical form which differs from that shown in FIG. 5 of the drawings with the forces and torques applied to the transfer bail being applied to corresponding surfaces of a bail having a different mechanical shape. Other variations in mechanical design could also be employed while using the underlying concepts of the invention.

What is claimed is:

1. An accumulator comprising:
a plurality of register elements representing respectively different orders, each register element being mounted for rotation;
means for making carries or transfers between register elements, said means including a plurality of transfer bails mounted with a single bail interconnecting each register element to the next higher order register element of the accumulator; and
means for shifting each said bail to one of three respectively different positions relative to the higher order register element in accordance with the position of the lower order register element.
2. An accumulator in accordance with claim 1 wherein each said register element includes a camming track, and wherein each said bail has a cam follower surface which engages said camming track.
3. An accumulator as defined in claim 1 wherein means are provided for shifting the position of all of said register elements relative to said bails, and wherein means are provided, including an extended portion of each said bail, for engaging the higher order register and introducing a carry into said higher order register upon the shifting of said register elements.
4. An accumulator as defined in claim 1 wherein each said register element includes a cam track for engaging one of said

bails and a series of digit elements for engaging another of said bails, and wherein each said bail includes a cam follower surface for engaging the cam track of the lower order register element with which it is associated and an extending portion for selectively engaging one of said digit elements of the higher order register element with which said bail is associated.

5. In a business machine:

an accumulator assembly having first and second accumulators including two sets of interleaved registers mounted on a single shaft;
 means for moving said accumulator assembly between a rest position and an operating position;
 a first set of U-shaped transfer bails interconnecting the registers representing successive orders of one of said accumulators;
 a second set of U-shaped transfer bails interconnecting the registers representing successive orders of the other of said accumulators; and
 means including said bails for positively and simultaneously advancing selected higher order registers to insert all carries upon movement of said accumulator assembly from the operating position to the rest position.

6. A business machine as defined in claim 5 wherein bails interconnecting registers in successive orders are provided with adjacent control surfaces, and wedges are provided to bear on said control surfaces and actuate the higher order bail to its transfer condition when the bails are appropriately positioned.

7. A business machine as defined in claim 5 wherein said registers are provided with cam surfaces and wherein said transfer bails include cam followers engaging said cam surfaces for orienting said bails to provide appropriate transfer action in the next higher order register.

8. A business machine as defined in claim 5 wherein said cam surface is provided with three cam zones, the first representing digits "1" through "8," the second representing "9" and the third representing "0."

9. A business machine as defined in claim 5 wherein one extension of at least one of said transfer bails is provided with a cam following means for actuation by a lower order register, and another extension of said bail is provided with a transfer means for mechanically engaging a higher order register.

10. A business machine as defined in claim 5 wherein latch means are provided for securing each bail in its operated position when the next lower order register passes through the "0" position.

11. In a transfer apparatus for handling carries between digital columns when two numbers are being added together;

a plurality of separate digital mechanisms for representing a plurality of digital orders;
 a plurality of inter-digit linkages, each having three positions for coupling between a lower order digit mechanism and the next higher order digit mechanism, one of said three positions being a normal position corresponding to register digits "1" through "8,"
 means for shifting each said linkage from said normal position to a second predetermined position when the lower order digit is "9,"
 means for shifting said linkage to a third predetermined "carry" position when the lower order digit has shifted from "9" to "0,"
 means for latching each said inter-digit linkage into the "carry" position;
 means for shifting only those of said linkages which are in the "9" position to the "carry" position if the adjacent lower order linkage is actuated to the carry position; and
 means for subsequently advancing by one digit each higher order digit mechanism associated with an inter-digit linkage in the "carry" position.

12. A transfer apparatus as set forth in claim 11 wherein means are provided for physically moving said digital mechanisms relative to said linkages following the entering of digital information and wherein said shifting means is operative as said digital mechanisms are moved.

13. In a transfer apparatus for handling carries between digital columns when two numbers are being added together;

a plurality of separate digital mechanisms for representing a plurality of digital orders;
 a plurality of inter-digit linkages, each having three positions for coupling between a lower order digit mechanism and the next higher order digit mechanism, one of said three positions being a normal position corresponding to register digits "1" through "8,"
 means for shifting each said linkage from said normal position to a second predetermined position when the lower order digit is "9,"
 means for shifting said linkage to a third predetermined "carry" position when the lower order digit has shifted from "9" to "0," and

means including wedges bearing on adjacent surfaces of adjacent inter-digit linkages for shifting only those of said linkages which are in the "9" position to the "carry" position if the adjacent lower order linkage is actuated to the carry position.
